MELTING FURNACE

Peter Marx, Hennef-on-the-Sieg, Germany

Application November 4, 1937, Serial No. 172,659
In Germany November 12, 1936

2 Claims. (Cl. 266—9)

The invention relates to melting furnaces for iron, steel and the like, and more particularly to the type adapted to be fired with powdered fuel.

One object of the invention is to provide a furnace comprising a cupola or stack for melting the constituents of the metal and a refining chamber into which the melted metal flows from the stack, and which is adapted to and has sufficient capacity for highly heating the metal for the production of metal of high quality and to overcome certain disadvantages and insufficiencies inherent in prior furnaces of this type.

Another object of the invention is to provide for retaining the hot gases in the refining chamber and producing high temperatures and efficient refining of the metal in the refining chamber by means of a tangential duct between the stack and the refining chamber with openwork refractory in the duct which delivers the hot gases into the stack for distribution throughout the cross-sectional area of the stack for rapid melting and also for heating the metal from the stack to the refining chamber.

Other objects of the invention will appear from the detailed description.

The invention consists in the several novel features which are hereinafter set forth and are more particularly defined by claims at the conclusion hereof.

In the drawing: Fig. 1 is a vertical section of a melting furnace embodying the invention, on line 1—1 of Fig. 2. Fig. 2 is a horizontal section on line 2—2 of Fig. 1. Fig. 3 is a plan of the removable hearth of the refining chamber.

The invention is exemplified in a furnace comprising a circular cupola or stack 10 into which the charge of materials to be melted for iron, steel or other metal, is fed and in the lower end of which they are melted. This stack is provided with a removable bottom 11 covered by refractory 12 to provide access to the cupola for repairs. A circular refining chamber 13 is horizontally offset from the cupola, and comprises a convex roof 14 and a depending annular wall 15 which is built integrally with, or as an extension of, the wall of the stack 10. The stack and refining chamber are built of refractory material. A duct 16 leads tangentially from the refining chamber 13 and tangentially into the lower end of the stack 10 to deliver the combustion gases into the stack. Duct 16 is inclined downwardly from the cupola, and passes through the side of depending wall 15 of the refining chamber. Duct 16 has an inclined and stepped bottom 17 over which the melted metal from the stack will slowly flow into the

refining chamber. Duct 16 is filled with open-work refractory 18 to retard the flow of heat from the refining chamber sufficiently so that the melt in said chamber will be highly heated for the production of highly refined metal, while permitting the remainder to pass into the stack and melt the material in the stack. The refining chamber also comprises a hearth 19 with a central dome 20 and an upstanding annular wall 21 conforming to the wall 15 depending from the roof 14 of the refining chamber. This forms an annular space between the cylindrical circular wall 21 and the dome 20 for the metal being refined.

A series of three ducts 22 extend through the depending wall 15 of the refining chamber, for the burners for delivering blasts of fuel, preferably powdered fuel, for firing the furnace. The axes of these openings are arranged to blow the fuel tangentially into the refining chamber and cause it to swirl around, and over the metal on the hearth in the annular space around the dome.

The tangential delivery of the fuel under pressure through openings 22 will cause the products of combustion to travel in a circular path over the metal on the hearth to heat and agitate the metal to a high degree, so as to eliminate the sulphur and carbon and produce pure metal of a high quality. The hot gases, after heating the bath in the refining chamber, pass tangentially through duct 16 from said chamber into the stack 10. The tangential course of the cupola and contact with the refractory 18 and walls of duct 16, cause the gases to contact thoroughly with the charge in the stack and results in full utilization of the heat-units contained in the gases.

A duct 24 is formed in the annular side wall 21 and leads outwardly from the refining chamber, for discharging slag and ash while the furnace is in operation. This outlet is controlled by a suitable valve 25 so that the escape of hot gases from the refining chamber may be controlled, and to discharge the slag when necessary. The circular blast of the gases in the refining chamber blows the ash over, and the slag on, the melted metal on the hearth so it will traverse a circular course with the metal. A baffle 26 projects inwardly from the wall 21 and is adapted to skim off the slag and deflect it to the tangential discharge opening 24. An opening 23 is formed in the side wall 21 for drawing off the refined melted metal from the hearth 19.

The hearth of the refining chamber with its annular wall 21 is separately built from the roof 14 and its depending wall 15 and is suitably supported so it can be lowered onto a wheeled truck /

27 to permit it to be transported to and from the upper section. This makes the hearth conveniently accessible for repair or relining. A plug 29 is provided in the hearth so the residue in the refining chamber can be discharged from the hearth.

In operation of the furnace, the charge of metal and materials to be melted is fed into the stack 10. The blasts of fuel delivered under 10 pressure into the refining chamber through inlets 22 cause the combustion gases to travel in a circular path indicated by arrows in Fig. 2 so the melted metal will be highly heated and refined. From the refining chamber the hot gases pass 15 tangentially through duct 16 and around the refractory 18, and into the lower portion of the stack 10 and melt the charge therein from its bottom upward. These gases enter the cupola tangentially to contact with all portions of the charge in the stack. The refractory material 18 in the duct 16 retards the flow of the hot gases sufficiently to maintain a very high temperature 20 in the refining chamber. The lower portion of the charge in the stack progressively melts and slowly trickles over the stepped floor 17 of duct 16 into the refining chamber and onto hearth 19. The dome 20 confines the melted metal to the annular space between the annular wall 21 and the dome. The cross-sectional shape of the melted 25 metal over the hearth will be such that its top surface will be of greater area than the portion beneath it, to provide ample space for the slag and impurities to be released from the melt in the refining chamber.

The circular blast in the refining chamber over the melt produces a circular motion of the metal and slag over the hearth. The baffle 26 skims the slag off the surface of the circularly-moving melt and deflects it to the discharge duct 24 which leads tangentially from the refining chamber. The discharge through duct 24 is controlled by means of valve 25 to avoid unnecessary escape of heat from the refining chamber. The valve 25 may be left open sufficiently to permit the slag, ash and impurities to be discharged continuously during the operation of the furnace or may be intermittently opened.

The furnace is adapted for continuous melting because the stack may be kept charged with metal and materials since they are melted at the bottom of the stack and then flow through the duct 16 to the refining chamber. The refined material 5 can be discharged during the refining and melting operation.

A characteristic of the refining chamber is that the space above the melt is clear and unobstructed, and this provides ample combustion area 10 for highly heating the melt during the refinement.

The invention is not to be understood as restricted to the details set forth, since these may be modified within the scope of the appended 15 claims, without departing from the spirit and scope of the invention.

Having thus described the invention, what I 20 claim as new and desire to secure by Letters Patent is:

1. In a melting furnace for metals, the combination of a vertical stack for retaining the charge to be melted, a round refining chamber below and offset horizontally relatively to the stack, means for delivering fuel tangentially into 25 the refining chamber to cause the products of combustion to swirl around the refining chamber, and a duct leading tangentially from the refining chamber to the bottom of the stack, for delivering the products of combustion from the refining chamber into the stack to melt the charge and for conducting the melted metal from the stack to the refining chamber.

2. In a melting furnace for metals, the combination of a vertical stack for retaining the charge to be melted, a round refining chamber below and offset horizontally relatively to the stack, means for delivering fuel tangentially into 30 the refining chamber to cause the products of combustion to swirl around the refining chamber, and a duct leading tangentially from the refining chamber and tangentially into the bottom of the stack, for delivering the products of combustion from the refining chamber into the stack to melt the charge and for conducting the melted metal from the stack to the refining chamber.

PETER MARX.
